United States Patent Office

Des. 218,806
Patented Sept. 29, 1970

218,806

DEVELOPER POWDER CONTAINER

Richard C. Berg, Bloomington, Minn., assignor to Minnesota Mining and Manufacturing Company, St. Paul, Minn., a corporation of Delaware

Filed Oct. 20, 1969, Ser. No. 19,646

Term of patent 14 years

Int. Cl. D9—04

U.S. Cl. D9—224

FIG. 1 is a top view of a developer powder container embodying my design;

FIG. 2 is a side view thereof, the opposite side view being substantially a mirror image thereof;

FIG. 3 is a bottom view thereof; and

FIGS. 4 and 5 are views of the ends thereof.

I claim:

The ornamental design for a developer powder container, as shown and described.
